UNITED STATES PATENT OFFICE.

JAMES F. HARBIN, OF STATESVILLE, NORTH CAROLINA, ASSIGNOR OF ONE-EIGHTH
TO THOS. M. DALE AND ONE-FOURTH TO W. L. CORNELIUS, BOTH OF STATESVILLE,
NORTH CAROLINA.

TYPE-LINE-CUTTING ATTACHMENT.

1,175,259.

Specification of Letters Patent. Patented Mar. 14, 1916.

Application filed July 23, 1915. Serial No. 41,553.

To all whom it may concern:

Be it known that I, JAMES F. HARBIN, a citizen of the United States, residing at Statesville, in the county of Iredell, State 5 of North Carolina, have invented certain new and useful Improvements in Type-Line-Cutting Attachments; and I do hereby declare the following to be a full, clear, and exact description of the invention, such as 10 will enable others skilled in the art to which it appertains to make and use the same.

My invention relates to type line cutters for type setting machines and is adapted for use in connection with all type setting machines casting a line.

It is also my purpose to provide an attachment of the type named which can be readily associated with a type setting machine and actuated through the medium of 20 connection with a movable part of the machine and when so associated will receive the slug from the delivery slide, cut the slug to the desired length and eject same after being cut into the usual galley, the waste 25 portion cut from the slug being also ejected to another locality.

It is my further purpose to provide an attachment of the type named which will be simple in construction, easily applied, efficient in use, cheap to manufacture, and which will completely avoid the necessity 30 of removing the slugs from the galley and cutting same to the desired length through the medium of a manual or mechanical saw.

It is also my purpose to provide an attachment of the type named which will cut the slug cleanly without tearing or leaving a ragged edge which would necessitate subsequent trimming.

With these and other purposes in view the invention consists in the details of construction and in the arrangement and combination of parts to be hereinafter more fully described and particularly pointed out in 45 the appended claims.

In describing the invention in detail reference will be had to the accompanying drawings wherein like characters of reference denote corresponding parts in the several views, and in which—

Figure 1 is a side elevation showing the attachment associated with a type setting machine and connected with a moving part of the machine to effect the mechanical ac-

tuation of the attachment; Fig. 2, an enlarged section on the line 2—2 of Fig. 1; Fig. 2, an enlarged section on the line 3—3 of Fig. 1; Fig. 4, a view similar to Fig. 3 with the parts of the attachment in the position they would occupy just after the operation of cutting the slug is complete; Fig. 5, an enlarged section on the line 5—5 of Fig. 1; Fig. 6, a view looking at the inner side of the fixed member of the attachment; Fig. 7, a view looking at the inner side of the movable member of the attachment, and Fig. 8, a perspective view of the adjustable stop.

Referring to the drawings 10 indicates the delivery slide of a type setting machine and 70 11 one of the cams thereof.

My attachment is shown as comprising a fixed member A and a movable member B, both of said members being in the form of substantially flat rectangular plates. The 75 fixed member A is provided with an angular projection 12 at one corner through the medium of which the member is secured directly to the delivery slide 10. Formed on the inner side of the member A is a rib 13 80 which is extended over the projection 12. Also formed in the inner side of the member A is a transverse groove which intersects the rib 13 and divides the latter into two sections 15 and 16. The outer face of 85 each section 15 and 16 is beveled as at 17 for a purpose that will presently appear. It will be noted that the rib 13 is so disposed that it will constitute a slide for the slug when it is delivered from the slide 10 of the 90 machine. Formed in the member A parallel to the rib 13 is a slot 18 and on either side of this slot in the outer face of the member are ratchet teeth 19. Slidably mounted in the slot 18 is a stop C which includes a head 95 20 and a foot 21 connected together by a stem 22. The head 20 is disposed adjacent the outer face of the member A and is provided with a tooth 23 adapted for co-operation with the teeth 19. The stem 22 extends 100 through the slot 18 and the foot 21 is disposed adjacent the inner face of the member A. The tooth 23 is normally held in co-operative relation with corresponding teeth 19 on either side of the slot 18 by means of 105 a leaf spring 24, one end of which is anchored to the head 20 and the other end bears against the outer face of the member

- A. To adjust the stop C it is only necessary to lift the head 20 carrying the tooth 23 against the influence of the spring 24 and then move the stop to the desired position.
- 5 Upon releasing the head 20 the tooth 23 will again be forced into coöperative relation with the teeth 19 to hold the stop in its adjusted position.
- Formed in the member A adjacent the edge of the member remote from the rib 13 is a slot D extending parallel to the rib 13 and divided into sections 25 and 26 by a plate 27 mounted in the member A in line with the groove 14. Secured to the member A and extending across the slot B is a plurality of spring fingers 28 which are curved away from the inner face of the member A and are of course tensioned when the free ends thereof are forced toward the member.
- 10 Secured to the ends of the member A parallel to the groove 14 and against the inner face of said member in spaced relation to said inner face are guides 29 and 30 between which is slidably mounted the member B.
- 15 Formed in the inner face of the member B are recesses 31 and 32 disposed in spaced relation to each other and in alinement. Secured to the inner face of the member B and extending across the recess 31 is a plurality of resilient fingers 33 the free ends of which are connected by a strip 34 having a beveled face 35 adapted to coöperate with the beveled face 17 of the strip section 15 in a manner that will hereinafter appear. It
- 20 will be noted that the free ends of the fingers 33 and the strip 34 can be depressed into the recess 31. Also secured to the inner face of the member B and extending across the recess 32 is a plurality of spring fingers 36 the free ends of which are connected by a strip 37 having a beveled face 38 adapted to coöperate with the beveled face 17 of the strip section 16 as will hereinafter appear. It will also be noted that the free ends of
- 25 the fingers 36 and the strip 37 can be depressed into the recess 32. Formed in the inner face of the member B between the recesses 31 and 32 is a groove 38' in which is mounted a rotatable cutter 39 a portion of
- 30 which projects into the groove 14 of the member A.
- Formed on the member B is a relatively wide rib 40 which engages the free ends of the fingers 28 at the termination of the cutting stroke of the member B to positively eject the cut slug and the waste through respective sections 25 and 26 of the slot D.
- 35 Assuming the parts to be in the position shown in Fig. 1 the operation is as follows—
- 40 The stop C is set the desired distance from the cutter 39. When the molded slug is discharged from the slide 10 it will pass between the members A and B and along the rib 13 until it strikes the foot 21 of the stop.
- 45 It will be here noted that a rod 41 is slid-

ably mounted on the machine and has one end in operative engagement with the cam 11. The other end of the rod 41 is pivotally connected to a lever 42 mounted upon the machine and this lever is in turn connected to the member B by a link 43. After the slug has been delivered to the attachment as previously described the cam 11 will operate to force the rod 41 longitudinally and rock the lever 42. This movement of the lever 42 will slide the member B relatively to the member A toward the slide 10. During this movement of the member B the cutter 39 will pass into engagement with the slug and cut the same to the desired length. As soon as the cutter 39 has severed the slug the latter shall have passed over the strip 34 and the part cut off shall have passed over the strip 37. When this operation has been completed the cam 11 releases the rod 41 to the influence of a spring 43 which automatically moves the rod in the opposite direction. This movement of the rod will of course effect movement of the member B to the position shown in Fig. 1. As the member B moves under the influence of the actuation of the rod 41 by the spring 43 the strips 34 and 37 will carry with them respectively the slug and waste, said slug and waste during this movement of the member B being disposed respectively on the outer sides of the fingers 33 and 36. As this movement of the member B continues the slug and waste will eventually be brought into alinement with the slot sections 25 and 26 respectively and finally ejected through said slot sections by engagement of the free ends of the fingers 28 with the rib 40. A galley is suitably disposed to receive the cut slug when ejected through the slot section 25. This operation is repeated successively as the actuation of the type setting machine is continued.

It will be observed that while I have described one form of carrying the invention into practice I desire it to be understood that various changes in the details of construction and in the arrangement and combination of parts can be resorted to without departing from the spirit and scope of the invention as defined in the appended claims.

What is claimed is:—

1. A type line cutting attachment for type setting machines comprising slidably connected members adapted to receive a slug to be cut therebetween, means carried by one of the members and operating to cut the slug when the last named member is moved in one direction, and means operated by movement of the last named member in the opposite direction to eject the cut portions of the slug from between the members.

2. A type line cutting attachment for type setting machines comprising slidably connected members adapted to receive a slug to be cut therebetween, an adjustable stop car-

- ried by one member against which one end of the slug is adapted to engage to determine the line of cut, and means carried by the other member and operating to cut the slug when the last named member is moved in one direction, and means operated by movement of the last named member in the opposite direction to eject the cut portions of the slug from between the members.
- 10 3. A type line cutting attachment for type setting machines comprising slidably connected members adapted to receive a slug to be cut therebetween, a rotary cutter carried by one of the members and operating to cut the slug when the last named member is moved in one direction, and means operated by movement of the last named member in the opposite direction to eject the cut portions of the slug from between the members.
- 15 4. A type line cutting attachment for type setting machines comprising slidably connected members adapted to receive a slug to be cut therebetween, one of said members being provided with discharge openings through which the cut portions of the slug are adapted to be ejected, means carried by the other member and operating to cut the slug when the last named member is moved in one direction, and means carried
- 20 by the last named member adapted to engage the cut portions of the slug during opposite movement of the last named member and move said portion with the member to the openings in the first named member for ejection therethrough.
- 25 5. A type line cutting attachment for type setting machines comprising slidably connected members adapted to receive a slug to be cut therebetween, one of said members being provided with a discharge opening through which the cut portions of the slug are adapted to be ejected, means carried by the other member and operating to cut the slug when the last named member is moved in one direction, means carried by the last named member adapted to engage the cut portions of the slug during opposite movement of the last named member and move said portions with the member to the openings in the first named member, and means for ejecting the cut portions of the slug through said opening.

In testimony whereof, I affix my signature, in the presence of two witnesses.

JAMES F. HARBIN.
